J. H. FLAGG

MACHINE FOR MAKING PACKING WASHERS

Filed Nov. 1, 1921

UNITED STATES PATENT OFFICE.

JOSEPH H. FLAGG, OF WORCESTER, MASSACHUSETTS, ASSIGNOR, BY DIRECT AND MESNE ASSIGNMENTS, OF ONE-HALF TO THE GRATON & KNIGHT MANUFACTURING COMPANY, OF WORCESTER, MASSACHUSETTS, A CORPORATION OF MASSACHUSETTS, AND ONE-HALF TO LEWIS H. TORREY, OF WORCESTER, MASSACHUSETTS.

MACHINE FOR MAKING PACKING WASHERS.

Application filed November 1, 1921. Serial No. 512,088.

To all whom it may concern:

Be it known that I, JOSEPH H. FLAGG, a citizen of the United States, residing at Worcester, in the county of Worcester and Commonwealth of Massachusetts, have invented a new and useful Improvement in Machines for Making Packing Washers, of which the following, together with the accompanying drawings, is a specification.

10 My invention relates to the manufacture of cupped packing washers and has for its object to provide an improved method and a machine for making articles of the above described type that are more durable and 15 more uniform in quality than packing washers heretofore manufactured.

In the previous manufacture of cupped packing washers it has been customary to employ flat disks or blanks, generally circular in form, which are projected into a die opening smaller than the blanks by means of a punch. The punch forces the central portion of the blank with which it is in contact, into the die in a flat condition, while the remaining portions of the blank, not in contact with the end of the punch, are drawn into the die opening and shaped around the sides of the punch to form the cylindrical wall portion of the packing. It has always been necessary to trim the uneven edges of the wall portions, following the forming operation, and it has also been found that packing washers formed as described above are liable to crack and wear out at their corners owing to the weakening of the wall material as it is bent around the punch.

According to the present invention I provide an improved method of manufacture and an improved machine that is adapted to produce finished packings in one operation and is also adapted to produce cupped packings in which the cup walls are greatly strengthened by compressing and setting the fibres and are thereby made more wear resistant, as compared with cupped packings previously manufactured.

In the accompanying drawings,

Fig. 1 is a transverse sectional view showing a portion of the parts of my improved forming machine in position for the formation of a cupped packing.

Fig. 2 is a transverse sectional view showing the parts of Fig. 1 in position following the formation of a packing.

Fig. 3 is a fragmentary view showing the arrangement of the cam mechanism for operating the machine.

Fig. 4 is a view in perspective of a blank for a packing washer.

Fig. 5 is a view in perspective of the blank shown in Fig. 4 after it has been formed by my machine.

Fig. 6 is a view in perspective showing the appearance of a blank at an intermediate stage in the formation thereof by my machine.

Like reference characters refer to like parts in the different figures.

Referring to the drawings, the machine generally comprises a table 1 having upwardly extending guides 2 between which a slide 3 is mounted for vertical movement. The slide 3 is provided with a central opening 4 within which a plunger 5 is adapted to move. The plunger 5 is provided at its lower end with an opening 6 within which is received a cylindrical punch 7. The punch 7 is surrounded by a sleeve 8 in sliding engagement therewith and terminating at its lower end in a beveled edge 9, the purpose of which will be hereinafter described. The sleeve 8 is provided with an enlarged portion 10, the upper end of which is threaded and is received in a threaded opening 11 provided at the lower end of the slide 3. The inside diameter of the enlarged portion 10 of the sleeve 8 is great enough to allow the plunger 5 to be moved therein.

As best shown in Fig. 3, the upper portion of the slide 3 provides a pair of plane surfaces 12, each of which is adapted to be engaged by the surface of a cam 13 mounted on a drive shaft 14 which extends across the top of the machine between the guides 2. The plunger 5 also provides a plane surface 15 which is adapted to be engaged by a cam 16 mounted on the shaft 14 between the cams 13. From an inspection of the form of the cams shown in Fig. 3, it is apparent that rotation of the shaft 14 will cause the cams 13 and 16 to operate on the surfaces 12 and 15 respectively, and thereby cause separate

movement of the punch 7 and the sleeve 8 with respect to the table 1.

As best shown in Fig. 1, the table 1 is provided with an opening 17 within which is seated a die holder 18. The die holder 18 is provided with an opening 19 extending therethrough, the upper portion of the opening 19 being counterbored as shown at 20, to receive a die plate 21. The die plate 21 is provided with an opening 22 of somewhat greater diameter than the punch 7, and an anvil 23 fits closely in the opening 22. The anvil 23 is provided with a shoulder 24 which is normally held against the bottom 15 of the die plate 21 by means of a spring 25 located within the opening 19 and having its lower end supported by an anvil block 26. The anvil block 26 is externally threaded for cooperation with the lower threaded portion 20 of the opening 19 and is provided with a tool receiving portion 27 by means of which the block 26 may be turned to adjust the tension of the spring 25. The spring 25 normally maintains the top surface of the anvil 23 flush with the top surface of the die plate 21 and a projection 28, formed on the anvil 23, is adapted to be in alinement with a corresponding recess 29 provided in the bottom surface of the punch 7.

Having thus described the various parts entering into my invention the operation thereof is as follows:—A blank 30, which is generally circular in form, as shown in Fig. 4, is provided with a central opening 31 whereby the blank may be centered on the anvil 23 by the projection 28. The blank 30 is of somewhat greater outside diameter than the punch 7, its outer portion being supported by that portion of the die plate 21 surrounding the opening 22. A blank 30 having been thus positioned on the anvil 23, the shaft 14 is rotated to bring the punching and forming devices into operation, as will now be described.

Referring again to Fig. 3, it will be seen that with the shaft 14 turning in the direction of the arrow, the cam 16 will first engage the plane surface 15 of the plunger 5 and thereby cause the punch 7 to descend 50 and engage the blank 30 which is thus held firmly between the end of the punch 7 and the anvil 23. Further downward movement of the punch 7 will cause the blank 30 to be drawn into the opening 22 in the die plate 21, the spring 25 permitting the anvil 23 to yield under the pressure of the punch 7. As the blank 30 is drawn into the opening 22, it is obvious that the portions of the blank 30 immediately surrounding the opening 22 will be bent around the end of the punch 7 so that the blank 30 will then have an appearance somewhat as shown in Fig. 6. The blank 30 then is generally cup-shaped in form, but the rim of the wall portion 32 60 is very irregular, owing to the fact that the

outer peripheral portions of the blank 30 have been considerably compressed on being drawn into the die opening 22.

In so far as I am aware, all prior machines for forming cupped packing washers by pressure alone have been adapted to only form the blank as shown in Fig. 6, so that it has been necessary to trim the serrated edges of the washers following their removal from the machine, thereby adding considerably to the cost of production. As previously set forth, it is one of the objects of my invention to provide an improved method of manufacture and a machine which is adapted to produce a finished packing by a combined drawing and compressing operation, and this action of my machine will now be described in detail.

Referring again to Fig. 3, it will be seen that the plunger 5 is adapted to reach the end of its downward stroke when the cam surface *a*—*b* engages the surface 15, at which time the parts of the machine will occupy the position shown in Fig. 2. The spring 25 is here shown compressed to such an extent that the shoulder 24 of the anvil 23 rests against a lug 26^a extending upwardly from the anvil block 26, so that the anvil 23 is rigidly supported. The parts will remain in this position so long as the cam surface *a*—*b* remains in contact with the plane surface 15. When the punch 7 is moved downwardly, as described above, it carries the sleeve 8 with it in the same relative position as shown in Fig. 1, and the sleeve 8 will remain in this position on the punch 7 until the high points *c* of the cams 13 engage the plane surfaces 12. When this occurs, the sleeve 8 will move downwardly on the then stationary punch 7 to the position shown in Fig. 2. As the sleeve 8 is thus moved downwardly, its beveled edge 9 engages the rim of the wall portion 32 of the cupped blank 30 and crowds it downwardly against the then stationary anvil 23. It is apparent that this movement of the sleeve 8 tends to greatly compress and set the fibres of the material of the cup wall so that it will tend to completely fill the space between the punch 7, the end of the sleeve 8, the anvil 23 and the walls of the opening 22.

Further rotation of the shaft 14 will cause the cam surfaces *a*—*b* and *c* to pass off the surfaces 12 and 15, whereupon the punch 7 and the sleeve 8 are withdrawn from the die 21 by any suitable means usually employed in machines of this type to return the reciprocating member or slide to the top of its stroke. The withdrawal of the punch 7 and sleeve 8 will allow the spring 25 to expand and return the anvil 23 to the position shown in Fig. 1, where the completed washer may be removed therefrom. The completed article will then have the

appearance shown in Fig. 5, wherein the wall portion 32 will have a smooth beveled edge 32^a, and being closely compressed, as described above, will have considerable 5 rigidity and strength. It is also apparent that packings formed as shown in Fig. 5 will be extremely durable, particularly at the corners 33 where the compression of material is a maximum. This latter property of the packings formed by my improved machine, is in direct contrast to the packings formed by prior machines, as shown in Fig. 6, which were liable to crack at the corners, owing to the fact that the 10 thickness of the blank has been considerably 15 reduced by the forming operation.

From the foregoing it is apparent that I have provided an improved method of manufacture and an improved forming machine 20 that is adapted to produce finished cupped packing washers at a single operation, which washers will be more uniform and durable in quality than washers heretofore manufactured. While I have shown my invention embodied in a particular arrangement 25 of parts, it is not so limited, but is susceptible of various modifications within the scope of the appended claims.

I claim,

30 1. In a washer forming and compressing machine, the combination with a die provided with an opening, a reciprocable forming punch and a compressing sleeve movable thereon, and a yieldable anvil within said opening, of means for moving said punch to depress said anvil, means for rendering said anvil rigid following a predetermined amount of movement thereby, and means for moving said sleeve into said opening after 35 the said anvil is rigid.

40 2. In a washer forming and compressing machine, a rotating shaft, a reciprocable forming punch having a compressing sleeve movable thereon, and cams mounted on said shaft for directly engaging said punch and said sleeve.

45 3. In a washer forming and compressing machine, a rotating shaft, a reciprocable forming punch having a compressing sleeve movable thereon, and cams mounted on said shaft for operating said punch and said sleeve to cause axial movement of first the punch and then the sleeve after said punch has come to rest.

50 55 4. In a washer forming and compressing machine, the combination with a die provided with an opening and a yieldable anvil therein, a rotating shaft and a reciprocable

forming punch having a compressing sleeve movable thereon, of a cam mounted on said 60 shaft for moving said punch into the die opening, and a second cam mounted on said shaft for moving said sleeve into the die opening after the punch has come to rest.

5. In a machine of the class described, a plunger having rectilinear movement and adapted, by a drawing operation to impart cup formation to a blank, in combination with a sleeve, brought into operation after said plunger comes to rest, for applying 70 pressure to the upstanding cupped wall of said blank, by rectilinear movement against the same.

6. In a machine of the class described, a stationary blank support having a cylindrical opening, a plunger movable toward said support to draw a flat blank into said opening and impart a cup formation thereto, and a sleeve surrounding said plunger and movable after the plunger has come to rest 80 to compress the upstanding wall of the cupped blank.

7. In a machine of the class described, a stationary blank support having a cylindrical opening, a rotating shaft, a plunger 85 movable toward said support by a cam on said shaft to draw a flat blank into said opening and impart a cup formation thereto, and a sleeve surrounding said plunger and movable after the plunger has come to rest, by 90 a cam on said shaft, to compress the upstanding wall of the cupped blank.

8. In a device for forming and shaping leather packing cups, the combination with a die plate for supporting a perforated 95 flat blank of leather on its upper surface, said plate having an opening therein and an enlarged cylindrical recess below provided with a screw thread at its bottom, of a plunger fitting in said opening and having its 100 lower end in said recess, a bottom plate having a screw thread by which it is adjustably mounted at the bottom of said recess, a spring resting on said bottom plate for holding said plunger up with its upper surface flush with 105 the top of said plate, said bottom plate having a positive stop within the spring for limiting the downward motion of the lower plunger, a second plunger above the first having a smaller diameter than the opening in 110 said plate arranged to engage the blank, and a hollow plunger centered on said forming plunger and fitting it, and having a lower surface for shaping the top of the cup.

Dated this 27th day of October, 1921.

JOSEPH H. FLAGG.
